UNITED STATES PATENT OFFICE

JOHN P. FABER, OF DUNELLEN, NEW JERSEY, ASSIGNOR TO RANSOME CONCRETE MACHINERY COMPANY, OF PLAINFIELD, NEW JERSEY, A CORPORATION OF NEW JERSEY

LOADER BUCKET FOR CONCRETE MIXERS

Application filed June 2, 1925. Serial No. 34,281.

The improvements relate primarily to means for loading concrete mixers with the aggregates to be mixed, and particularly to what are commonly known as loading buckets. These loaders are constructed and arranged to rest on the ground below the charging opening of the mixer, so as to receive the said aggregates from barrows or shovels, or any other manner, near the ground level, and are provided with means for elevating them. The loader is usually so mounted that as it is raised it also tips or tilts and discharges its load into the mixer. A common arrangement is to have it mounted on a pivoted arm or frame, and the present improvements are designed to secure a better mounting and operation of a loader so mounted, and to economize the power required to elevate it with its load.

20 The improvements are illustrated in the accompanying drawings, in which

Fig. 1 is a side elevation of a loading bucket with connected parts embodying the improvements;

25 Fig. 2 is a similar view with the bucket raised to discharging position;

Fig. 3 is an end view of some of the parts looking from a point inside the mixer frame.

30 Fig. 4 is a diagrammatic view of a detail. The skip or bucket 1 is adapted to be raised or lowered by means of a cable 2 running over a sheave 3 and connected with a suitable power device. 4 represents the

35 hopper of the concrete mixing drum, adapted to receive the charge of concrete and pass it through the opening in the charging head 22 of said drum. 5 is an upright member of the frame of the apparatus, mounted on the base 14, one of said uprights being provided at each side of the tub, as indicated in Fig. 3. A top member 21 of the frame connects the uprights 5 with other parts of the frame.

40 A plate 6 with turned strengthening edges is pivoted at 7 in brackets 8 secured on the uprights 5 and extends across from one bracket to the other, and at 9 near the bottom of this pivoted plate the tub carrying frames are pivoted. These frames consist of

the converging arms 11 and 12 connected by the plate 10 to each other and to the pivot, the brace 18 connecting their outer portions, and the widened outer ends 19 and 20 secured to the upwardly extending portion of the loading tub or bucket 1. The inward movement of the pivoted plate 6 is limited by the stop 13 on the base 14, and the inward and upward movement of the bucket carrying frame is limited by contact between the plate 6 at its upper part near its edge and the stop 16 riveted at 17 to the outer portion of the frame 11.

55 The operation of the device is as follows.

The bucket receives its load in the position shown in Fig. 1, and then is raised by the cable 2. This causes it to pivot on the axis 9 until the check member 16 strikes the pivoted hanging plate 6. The parts then swing on the pivot 7 until the bucket reaches the position illustrated in Fig. 2, where it discharges its loading into the mixer. It will be seen that by this arrangement the line of pull of the cable 2 is substantially tangential to the arc described by the bucket carrying frame until the bucket reaches an elevation in which its outer part is above horizontal position and its load commences to discharge. This makes the movement of raising the load to discharging position a comparatively short one requiring a minimum of power directly applied. The further inward and upward swing of the bucket on the pivot 7 is also relatively short and is aided by the movement of the materials toward the discharge end.

80 The pivot 7 is in the form of a rod running through the turned sides of the member 6 and the brackets 8, and the pivot 9 is a similar or shorter bar extending through the sides of the member 6 in like manner and through the plate 10 of the pivoted bucket carrying frames. One of these frames is located on each side of the member 6, and connected to opposite sides of the bucket. The member 6 is preferably in the form of a plate of heavy sheet metal with its vertical side edges turned inwardly, but it may be made in other form, such as two side members connected by cross pieces, if 85

desired. The form shown, however, has the advantages of strength, simplicity and easy of assembling. The check member 16 extends across from one member 11 to the other, and forms a brace as well as a stop. It comes in contact with the pivot bar 7 between the edges of the outwardly turned sides of the part 6 when the bucket reaches the position of Fig. 2. Another feature of the movements consists in the manner of running the cable 2 and connecting it with the bucket. This cable runs over a sheave on each side of the frame at the top and through a bale 23 entering the bale at one side of the bucket extending around under it and passing out at the other side. The bale is connected with the bucket by a pivot 24 on each side so that there is a certain amount of pivotal movement between the two parts. This equalizes the pull of the cable on the bucket, and also protects the cable against undue wear and injury or the deteriorating effect of exposure to the ground, as where it is run under the bucket. A diagrammatic view of the parts mentioned is shown in Fig. 4.

What I claim is:

1. In a device of the character described, a supporting frame, a loader bucket having charging and discharging portions at an angle to each other, means for elevating same comprising a cable attached to the bucket and extending to the upper part of the frame and a source of power connected with said cable, a member pivotally mounted on said frame and extending downwardly therefrom, and a second member pivoted to the lower portion of the first member and extending laterally therefrom to the bucket when the said bucket is in loading position, said member composed of parts extending from the pivot on divergent lines secured to the bucket at different points, a jaw shaped member mounted on said second member and positioned for contact with the pivot of the first named member for supporting said bucket in its final arcuate travel, the construction and arrangement being such that the bucket in rising first moves on the pivot of the second member to a position in which its outer portion is above horizontal position and its inner or discharging portion is in approximately horizontal position, and then swings inwardly and upwardly on the pivot of the first and downwardly extending member.

2. In the device specified in claim 1, a stop on the frame limiting the movement of the first-named member away from its bucket elevating position and a check member extending from the second member and adapted to come in contact with the pivot of the first member on the upward movement of the former.

3. In the device specified in claim 1, the

said first member consisting of a plate having turned edges, extending substantially from side to side of the bucket.

4. In the device specified in claim 1, the said elevating means being connected with the bucket at a medial point and opposite the second pivoted member.

5. In the device specified in claim 1, a portion of the second pivoted member being above horizontal position when the bucket is in its lowermost or loading position.

6. In a device of the character described, a supporting frame, a loader bucket having charging and discharging portions at an angle to each other, means for elevating same comprising a cable attached to the bucket and extending to the upper part of the frame and a source of power connected with said cable, a member pivotally mounted on said frame and extending downwardly therefrom, and a second member pivoted to the lower portion of the first member and extending laterally therefrom to the bucket when the said bucket is in loading position, a jaw shaped member mounted on said second member and positioned for contact with the pivot of the first named member for supporting said bucket in its final arcuate travel, the construction and arrangement being such that the bucket in rising first moves on the pivot of the second member to a position in which its outer portion is above horizontal position and its inner or discharging portion is in approximately horizontal position, and then swings inwardly and upwardly on the pivot of the first and downwardly extending member.

7. The combination with a mixing vessel and a frame for supporting the same, of a loader bucket for the mixing vessel, means for pivoting said bucket with reference to the frame consisting of a pendentially hinged link, said link having a hinged connection at its free end with the loader bucket, said hinged connection having a jaw member positioned to engage the hinge of said link for supporting the loader bucket during final travel to charging position, and means for raising the bucket first on the lower axis and then on the other to mixing vessel charging position.

8. The combination with a mixing vessel and a frame for supporting the same, of a loader bucket for the mixing vessel, means for pivoting said bucket with reference to the frame consisting of a pendentially hinged link to oscillate from one side of a vertical line from its hinging axis to the other, said link having a hinged connection at its free end with the loader bucket, said hinged connection having a jaw member positioned to engage the hinge of said link for supporting the loader bucket during final travel to charging position, and means for raising the

bucket first on the lower axis and then on the other to mixing vessel charging position.

9. The combination with a mixing vessel and a frame for supporting the same, of a loader bucket for the mixing vessel, means for pivoting said bucket with reference to the frame consisting of a pendently hinged link, said link having a hinged connection at its free end with the loader bucket, said 10 hinged connection having a jaw member positioned to engage the hinge of said link for supporting the loader bucket during final travel to charging position, and means for raising the bucket first on the lower axis and 15 then on the other to mixing vessel charging position and a stop for limiting the swing of said link at its innermost position.

10. The combination with a mixing vessel and a frame for supporting same, of a loader bucket for the mixing vessel, means for pivotally supporting said bucket for swinging through different arcs comprising a depending link having a pivot connecting it at its upper end to said frame, a frame 20 fixed to said bucket and having a pivot connecting it with the lower portion of said link, a supporting jaw on said last named frame, the distance between said jaw and second pivot being substantially equal to 25 the distance between said pivots, and means for swinging said bucket in an arc about said second pivot until said jaw contacts said first pivot and thence for swinging said bucket in an arc about said first pivot while 30 said bucket is supported thereon by said 35 jaw.

Witness my hand this 1st day of June, 1925, at the city of New York, in the county of New York, State of New York.
